SANITARY ASHCAN AND GARBAGE CAN

Martin Glowka, New York, N. Y.

Application January 27, 1937, Serial No. 122,517

2 Claims. (Cl. 220—81)

This invention relates to new and useful improvements in a soldered sanitary strip for ash cans, and garbage cans.

Heretofore ash cans and garbage cans have been constructed with double turned in seams of unprotected material which were subjected to great strain when the ash cans were thrown about during ash removal. Consequently, the seams would buckle open and the ash cans would spill some of their contents. This has been particularly objectionable when the cans contained garbage, as then the garbage would litter the street. Many cities have ordinances prohibiting the use of such defective ash cans and quite often janitors and others using these ash cans are given summonses by health officers because of violation of these sanitary ordinances.

This invention has for an object the provision of means associated with a conventional ash can by which the double turned in seams are reinforced to prevent their opening as above explained.

Still further the invention particularly contemplates the attachment of reinforcement strips along the seams for two purposes: First, to themselves receive shocks and pressures to which the ash can is subjected, and second, to cover up the weak double turned in seam and so reinforce it.

Still further the invention proposes the association of a packing element with the seam and an arrangement for forcing the packing element into the seam so as to re-close the seam should it open accidentally. It is further contemplated to so arrange these parts so that they simultaneously protect the seam from direct blows when the ash can is being handled.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an ash can constructed according to this invention.

Fig. 2 is a horizontal sectional view taken on the line 2—2 of Fig. 1.

Fig. 3 is a fragmentary sectional view taken on the line 3—3 of Fig. 1.

Fig. 4 is a perspective view of a household garbage can of the type having a cover capable of opening when one steps on a foot lever, which can is modified to include the features of this invention.

Fig. 5 is a fragmentary side elevational view of the seam portion of an ash can constructed according to a modification of this invention.

Fig. 6 is a sectional view taken on the line 6—6 of Fig. 5.

The ash can, according to this invention, comprises a standard ash or garbage can 10 having a conventional double turned in seam 11 extending from the top to the bottom, formed during the manufacture of the can, which is constructed from sheet material. This ash can also has a set in bottom 12 connected with the side of the ash can by another double turned in seam 13. A strip of material 14 is extended over the seam 11 and extends its complete length and is secured to the material of the ash can by known methods. It may be soldered, braided, welded, or attached in any other manner.

A plurality of reinforcing plates 14' may also be riveted to the can 10 over the seam 11 of the ash or garbage can and a suitable handle 10' riveted on top of one of these plates. The ash can is provided with a cover 15 adapted to engage tightly over the top of the ash can and over the top end portion of the strip 14.

At the bottom the double seam 13 is reinforced by two strips. There is an outer annular strip 16 engaged about the lower portion of the ash can, and an inner annular strip 17 engaged around the inside of the double turned seam 13. This inner annular member 17 is of angle shape in transverse cross section. Both the strips 16 and 17 are soldered, braided, welded or in any other manner attached to the material of the ash can.

In Fig. 4 a household garbage can 18 is illustrated to which the invention has been applied. This garbage can has a cover 19 which is operated by a link 20 connected with a foot pedal 21. The details of this garbage can will not be given in this specification since they form no part of the invention, and similar constructions are generally known. This can 18 is provided with a reinforcement strip 14^a extended over and protecting the double turned side seam thereof. There is also an annular member 16' extended over and attached to the bottom portion of the can 18 for protecting the bottom seam.

In Figs. 5 and 6 a modification of the invention has been described in which there is provision for packing the seam in the event that it opens slightly during the use of the ash can. More specifically, an ash can 10'' is illustrated with a side double turned in seam 11''. A plate 23 is extended across this double turned in seam and is slidably supported by spaced studs 24 mounted on the

body of the ash can and working in slots 25 formed in the plate 23. The outer edge portion of the plate 23 has a hooked bent in portion 23^a which engages against the split end 26' of rubber packing or similar packing material 26 which is caught in by a portion of the double turned in seam 11''. The hook portion 23^a engages the split end 26' and forces one side portion thereof against the side of the ash can and the other portion against the side portion of the double turned in seam 11''.

5 A tensioning device is associated with the plate 23 for applying pressure against the packing element 26. This pressure means comprises spaced studs 27 attached at spaced positions on side portions of the plate 23 and extending through brackets 28. Nuts 29 are engaged on the studs 27 and act against the brackets 28 for providing the required pressure at the packing element 26. Should the seam 11' slightly open due to rough 10 handling of the can, or for other reasons, the nuts 29 may be turned further downwards to force the packing 26 further into the open seam and so tend to close it. The plate 23 extends across the double seam 11' for protecting it.

15 20 25 30 25 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. In an ash can, a double turned in seam, a sheet of resilient material clamped in said seam and extending therefrom, a protecting strip engaged over said seam and having an offset edge portion engaging said resilient sheet for clamping said resilient material against the side of the seam and the side of the can, means for slidably supporting said strip on said can, and means for forcing said strip laterally to increase its pressure and change its position in relation to said resilient material.

2. In an ash can, a double turned in seam, a sheet of resilient material clamped in said seam and extending therefrom, a protecting strip engaged over said seam and having an offset edge portion engaging said resilient sheet for clamping said resilient material against the side of the seam and the side of the can, means for slidably supporting said strip on said can, and means for forcing said strip laterally to increase its pressure and change its position in relation to said resilient material, comprising several studs attached upon said strip, brackets on said can through which said studs extend, and nuts threadedly engaged upon said studs and acting against said brackets.

MARTIN GLOWKA. 30
